UNITED STATES PATENT OFFICE.

JOSEPH C. DONNELLY, OF BARBERTON, OHIO, ASSIGNOR TO THE DIAMOND MATCH COMPANY, OF CHICAGO, ILLINOIS, A CORPORATION OF ILLINOIS.

BOX-FILLING MACHINE.

1,248,465.

Specification of Letters Patent.

Patented Dec. 4, 1917.

Application filed October 3, 1916. Serial No. 123,482.

To all whom it may concern:

Be it known that I, JOSEPH C. DONNELLY, a citizen of the United States, and resident of Barberton, in the county of Summit and 5 State of Ohio, have invented certain new and useful Improvements in Box-Filling Machines, of which the following is a specification.

This invention relates to a machine for 10 filling match-box trays with matches, and particularly to machines of the kind wherein a succession of temporary holders (from which the matches are subsequently transferred to the box trays) is impelled in a 15 path adjacent the discharging station of a match-making machine and thereby progressively supplied with matches. A box filling machine of the character mentioned is illustrated in Letters Patent of the United 20 States No. 836,730, dated November 27, 1906, to which reference may be had.

The object of my invention is to accomplish the orderly and compact disposition within the progressing temporary holders 25 of a box filling machine of the matches discharged from the carrier of a match machine; and to this end the invention comprises, in a box filling machine, an endless 30 succession of temporary holders having therein movable bottom members which are gradually lowered during the progress of the holders across the path of the falling matches from the match machine.

The invention also comprises means where- 35 by a series of short rapid vertical vibrations are imparted to the successive bottoms of the temporary holders during their travel through and preferably some distance beyond the filling zone.

40 The invention also comprises various novel features of construction and combinations of parts, all of which will be hereinafter described and claimed.

In the annexed drawings—

45 Figure 1 is a plan of a chain of temporary match-holders, and its associated parts, embodying my invention, a part of the match-making machine being illustrated.

50 Fig. 2 is an elevation, partly in section, of a portion of the chain of match holders and adjuncts; some of the spring actuated pins for the movable bottoms of the holders being broken off for clearness.

55 Fig. 3 is a transverse vertical section through the chain and adjuncts, on a plane

through one of the sprocket wheels, as on the line 3—3 of Fig. 1.

Fig. 4 is a vertical section, on a larger scale, through several of the temporary holders, showing a portion of the jarring 60 mechanism therefor.

Fig. 5 is a sectional perspective view of the guiding structure for the chain of temporary holders, showing a portion of the chain and adjuncts. 65

Fig. 6 is a transverse section on a plane through the match carrier and punch mechanism of the match machine and the adjacent part of the temporary holder mechanism, as on the line 6—6 of Fig. 1.

70 Referring to the drawings, 10 designates one of the perforated match carrier plates of a match machine; and 11 a reciprocating head carrying punches 12 for ejecting the matches row by row from the perforations 75 of the carrier.

13 designates a horizontal bed supported on a plane below the path of discharge of the matches from the carrier; 14, 15 vertical shafts journaled in bearings at or near 80 the respective ends of the bed; 16, 17 sprocket wheels on said shafts, and 18 an endless chain passing about the wheels so as to travel in a path adjacent the match carrier in the region of the discharge station. The chain 85 is provided throughout its length with receptacles constituting temporary holders which are adapted to receive and assemble the matches as rapidly as they are discharged from the match machine. In another part of 90 the travel of the chain the matches are transferred from the temporary holders into the box trays as described in the Patent No. 836,730 above referred to. The bed is provided with spaced up-standing walls 19 95 which afford a run-way within which the chain of holders is supported and guided; said walls being suitably recessed or cut-away for the reception of the sprocket wheels and also to afford ample space for the end- 100 wise removal of the matches from the temporary holders.

105 The temporary holders, which form, in effect, links of the sprocket chain, comprise flat rectangular bottom plates 20 provided each with end walls 21 and an intermediate division wall 22, the two chambers or compartments thus formed being open at their respective ends. Each of the chambers is equal to or slightly greater in length than 110

the matches and is of a width and height to receive and hold an excess quantity of matches for a box tray. The adjoining end walls of the train or series of holders are in close proximity to each other, and their upper edges, including those of the central walls, are preferably beveled or tapered, as shown, to facilitate the entrance of the matches to the chambers.

10 The shaft 15 of the sprocket wheel 17 carries at its lower end a bevel gear wheel 23 in mesh with a similar wheel 24 on a horizontal shaft 25 that is driven in any suitable manner.

15 The parts thus far described are or may be of the construction and operation illustrated and described in Patent No. 836,730 aforesaid.

Within each of the match chambers is a 20 vertically-movable bottom member 26 from which spaced pins 27 depend through guide orifices in the bottom plate 20 of the holder structure; the lower ends of the pins being provided with heads 28. Springs 29 encircling the respective pins and bearing against the bottom plate 20 and the heads 28 tend to maintain the member 26 yieldingly down upon said plate. The upper surface of the bottom member is channeled 25 to provide a shallow open end trough having upwardly and outwardly inclined sides 30 for a purpose which will presently appear.

Affixed to the member 26 is a plunger 31 35 which depends through a central guide bushing 32 on the bottom plate. The length of the pin is such that its lower or free end lies slightly above the bed 13 when the member 26 is in its lowermost position, such end 40 being preferably shaped to provide an inclined contact portion 33.

Affixed to the bed, directly beneath and parallel with the stretch of the chain of temporary holders adjacent the match carrier, and in the path of the depending plungers from said holders, is a bar 34 having on its upper edge a series of toothed or serrated surfaces 35 which are arranged in step-like order descending from a point adjacent the outer or right hand edge of the match carrier to a point adjacent the inner or left-hand edge of said carrier. The length of each of the surfaces is substantially equal to the distance between the centers of the two chambers or compartments of a temporary holder, excepting the lowermost surface which is preferably extended some distance along the bed, as indicated at 36. The outer or right-hand end of the 50 upper step merges with a smooth surface 37 which gradually declines toward the bed, whereby the plungers of the traveling holders successively impinge against the surface 37 and are thereby gradually raised in a 55 manner to elevate the succeeding bottom

members to their highest position; thence passing from one step surface to another and permitting the lowering of the bottom members to their lowermost position within the temporary holders.

When the successive bottom members are at their highest level they are positioned in proximity to the plane of discharge of the matches from the adjacent part of the match carrier, and hence the descent of the matches 70 is slight, thus obviating liability of the disarrangement of the falling matches. As each temporary holder progresses in front of the match carrier the bottom member of the holder is lowered a distance equal to 75 the thickness of a match, or substantially so, thus providing for the reception of a superposed row of matches; and so on the bottom member is progressively lowered and the matches are delivered to the holder until it 80 has passed beyond the match carrier, whereupon the holder is in its lowermost position and contains a complement of matches 85 requisite for delivery to a match tray.

As the spring pressed plungers pass along 90 the step surfaces of the bar the plungers and therewith the attached bottom members are vertically vibrated by the action of the teeth or serrations, thereby jarring the matches and causing them to settle within 95 the holders, and since the filled holders travel some distance beyond the carrier with the plungers in engagement with the serrated extension of the bar the agitation of the said members is continued in a manner 100 to insure the orderly and compact arrangement of the matches within the holders preparatory to their passage to the discharge station.

Preferably each of the toothed or serrated 105 steps is slightly inclined upwardly from the right to the left hand end thereof as shown, in order to enable an extended drop of each pin and a substantial jar to the matches in the associated temporary holder as the pin 110 passes from one step to another. Thence the holder in its progress along the lower step is slightly raised and subjected to a series of slight vibrations, which in conjunction with the initial jar insure the efficient settling of the matches within the box 115 trays.

The quantity of matches delivered to each holder as it approaches and crosses the right-hand edge of the match carrier of the 120 match machine is somewhat less than the quantity supplied to the holder when the latter is progressing in front of the body of the carrier, and hence the bottom member is recessed or channeled as above described 125 in order that the parallelism of the matches imposed upon said member may be maintained until the holder has advanced sufficiently for the delivery of matches thereto throughout its width.

The endless chain 18 travels upon a raised supporting track 38 therefor on the bed, which track constitutes the basal part of the inner wall of the runway.

- 5 The inner sides of the longitudinal walls of the run way adjacent the match machine are preferably provided with rails 39, having tongues 40 which register with longitudinal end grooves 41 in the succeeding bottom plates of the traveling temporary holders, and thus maintain the holders in a fixed horizontal plane during the vertical movements of the members 26. The rail on the outside wall is preferably continued 10 about the curved ends of the runway and it is provided throughout its length with a flange 42 which affords a supporting track for the adjacent ends of the holders during their travel. A rail section 39', provided 15 with a track flange 42' is secured to the inner side of the outer reduced wall of the run way so as to support the outer ends of the holders as they pass along said outer wall; the flange 42' constituting, in effect, 20 25 a continuation of the track flange 42.

As a simple and efficient means to avoid liability of vertical displacement of the bottom members of the filled holders, as they pass around the sprocket wheel 16, I preferably provide the inner basal track portion 38 of the outer curved wall of the runway with a curved section having an inwardly projecting semicircular rib 43 which registers with suitably-disposed slots or recesses 35 44 in the lower portions of the pins of the successive holders, as the latter approach and pass around the sprocket wheel.

I claim—

1. In a box-filling machine having a succession of match holders arranged to travel adjacent the discharge station of a match machine, the combination with said holders, of vertically-movable bottom members there-in, and means for successively raising said members as they approach the discharge station of the match machine and for gradually lowering and vertically jarring said members in their continued travel adjacent said station.
2. In a box-filling machine having a succession of match holders arranged to travel adjacent the discharge station of a match machine, the combination with said holders, of vertically-movable bottom members there-in, and means for successively raising said members as they approach the discharge station of the match machine, then gradually lowering and vertically jarring said members in their continued travel adjacent said station, and thereafter vertically-jarring said members in an interval of their travel.
3. In a box-filling machine having a suc-

cession of match holders arranged to travel adjacent the discharge station of a match machine, the combination with said holders, of vertically-movable bottom members there-in, depending plungers on said members, and an actuating element for said plungers adjacent the discharge station, said element having an upwardly inclined surface upon which the plungers are successively raised as they approach said station and having also a series of toothed or serrated step surfaces descending from the summit of the inclined surface toward the opposite side of the discharge station.

4. In a box filling machine having a succession of match holders arranged to travel adjacent the discharge station of a match machine, the combination with said holders, of vertically-movable bottom members there-in, depending plungers on said members, spring means to maintain said members normally depressed, and a bar arranged longitudinally of the path of the plungers as they approach and travel adjacent the said discharge station, said bar having an upwardly inclined approach for the plungers to the discharge station and having also a series of toothed or serrated step surfaces descending from the summit of the approach toward the opposite side of the discharge station.

5. In a box filling machine having a succession of match holders arranged to travel adjacent the discharge station of a match machine, the combination with said holders of guide means therefor adjacent the discharge station, vertically-movable bottom members in said holders, means for maintaining said members normally depressed within the holders, and means for successively raising said members as they approach the discharge station of the match machine and for gradually lowering and vertically jarring said members in their continued travel adjacent said station.

6. In a box filling machine having a succession of match holders arranged to travel adjacent the discharge station of a match machine, the combination with said holders, of vertically-movable bottom members there-in having laterally tapering channels, and means for successively raising said members as they approach the discharge station of the match machine and for gradually lowering and vertically jarring said members in their continued travel adjacent said discharge station.

Signed at New York in the county and State of New York this 2nd day of October A. D. 1916.

JOSEPH C. DONNELLY.
